GAME DEVICE

Edward A. Walsh, Mount Vernon, N. Y.

Application October 3, 1939, Serial No. 297,635

4 Claims. (Cl. 273—141)

Numerous games have been devised which depend upon the skill of the player. There are just as many, if not more, the outcome of which depend upon pure chance. The former, as backgammon, chess and the like, take up space and consume considerable time; and the latter, such as roulette, are also bulky and moreover, their use is prohibited in many States.

Among the points to be desired in a game device are first, simplicity and compactness, second, durability, third, it should be easy to play, and last, it should require but a few seconds to play a single game.

I have invented a game in the nature of a spinner, which fulfills all the aforementioned desired requirements, and enables two people to indulge the gambling instinct—inherent in most persons—as many times as fancy dictates. The device can be carried in the pocket, placed on a bar, table, or other place for playing, and instantaneously removed at will.

In brief, the invention comprises a base or pedestal, with a perpendicular socket, adapted to receive a spindle, on the outer end of which there is an indicator. The mounting of the spindle, in conjunction with its socket, whereby extreme velocity of the indicator and prevention of lateral thrust may be obtained, is one of the salient features.

30 In the drawing:

Fig. 1 is a perspective view of the spinner, Fig. 2 presents a transverse section thereof,

Fig. 3 illustrates an enlarged cross section of the indicator and spindle assembled with the bearing,

Fig. 4 is a perspective view of the spindle, and Fig. 5 is a similar view of the socket.

With more particular reference to the drawing, 5 indicates a base or pedestal, preferably of circular contour and slightly convex, with a line 6 extending diametrically to divide the upper surface of the base into halves, which may bear any suitable indicia, in accordance with the specific nature of the game it is desired to play. The upper 40 surface may be similarly laid out in segments of varying dimensions with appropriate notations or legends, should the occasion so require.

Secured medially of the base 5, as by means of upsetting the depending lug 7, is a vertically disposed socket 8—best seen in Fig. 5—the lower portion of which is rounded off as at 9, to receive an anti-friction bearing 10, while the upper terminal is provided with an internal annular recess 11, of greater diameter than the central, counter bore or concavity 12 of the socket,

with the result that there is formed a seat 13, and a relatively thin, pliant, side wall 14.

The spindle 15, as exhibited in detail in Fig. 4, is an integral unit, consisting of a shank 16 and a pair of annular flanges or projections 17 and 18, the former being substantially conoidal and the latter presenting the contour of a flat, circular flange with an upstanding stub 19.

In assembling the elements of the invention, spindle 15 is inserted in socket 8 with the lower 10 end of shank 16 resting upon anti-friction bearing 10 and the bottom of flange 17 engaging seat 13 of recess 11. So positioned, wall 14 of recess 11 is contracted until it lies against the angular, inclined outer wall of flange 17—see dotted lines 15 in Fig. 3—with the result that a bearing for the spindle is afforded at two points, namely, (1) by the anti-friction element 10 and (2) by the seat 13 of recess 11, whereby a true axial rotation of the spindle within its complemental socket and 20 the total absence of any lateral thrust is insured. A further point in this connection is that because of the lesser diameter of shank 16 than the internal bore 12 of socket 8, the shank is rendered devoid of friction along the entire extent 25 of its vertical wall.

Flange 18 serves as a support for any kind of a suitable indicator 20, the connection at this point being secured by upsetting stub 19.

In practical operation, the indicator is 30 impelled with one's finger, either by a pushing or flipping movement, and due primarily to the novel mounting of the spindle within the socket, the indicator proceeds to rotate at a high rate of speed, depending, obviously, upon the force 35 exerted by the finger. The outcome of the game depends upon which side of the line 6 of base 5 the pointer end of the indicator comes to rest.

The compactness of my invention and facility of playing admits of universal use, wherever men 40 or women meet and wish to indulge in a quick game of chance. Its durability assures an almost indefinite life.

It should be understood that in broader aspects, the invention comprehends not only the 45 various means described, but equivalent means for performing the recited functions. Applicant reserves the right to effect such modifications or changes as may come fairly within the scope of the following claims.

50 I claim:

1. A spinner comprising, in combination, a base, a vertical socket carried by the base and provided with an annular seat at its outer terminal, a pliant wall extending from said seat, 55

- an anti-friction bearing disposed in the bottom of the socket, a spindle having a shank resting on said bearing and formed at its outer extremity with an annular projection engageable with said seat, said wall being bent towards said projection, said shank being freely rotatable within the socket between said seat and bearing, and an indicator carried by the outer end of the spindle.
- 10 2. A spinner comprising, in combination, a base, a vertical socket carried by the base and provided with an annular recess at its outer terminal, an anti-friction bearing disposed in the bottom of the socket, a spindle having its lower end resting on said bearing and formed at its outer extremity with an annular projection engaging the inner surface of said recess, the wall of said recess being inturned against the side of said projection, and an indicator mounted upon the outer end of the spindle.
- 15 3. A spinner comprising, in combination, a base, a vertical socket carried by the base and provided with an annular recess at its outer terminal, an anti-friction bearing disposed in the bottom of the socket, a spindle having its lower end resting on said bearing and formed at its outer extremity with an annular projection engaging the inner surface of said recess, the wall of said recess being inturned against the side of said projection, and an indicator mounted upon the outer end of the spindle.
- 20 4. A spinner comprising, in combination, a base, a vertical socket carried by the base and provided with an annular recess at its outer terminal, an anti-friction bearing disposed in the bottom of the socket, an integral spindle having its lower end resting on said bearing and formed at its outer extremity with a pair of annular projections, one of said projections engaging the inner surface of said recess, the wall of said recess being inturned against the side of said projection, and an indicator mounted upon the other projection.

EDWARD A. WALSH.
